THREAD HOLDING AND CUTTING DEVICE

Laura K. Track, Brooklyn, N. Y.

Application November 11, 1943, Serial No. 509,865

8 Claims. (Cl. 242—139)

1

This invention relates to new and useful improvements in a thread holding and cutting device.

More particularly, the invention contemplates an improved device as mentioned which may hold spools of thread of various sizes, and which may be used at home or in commercial establishments. An important feature of the new thread holder resides in the fact that the threads will always be separated and will not become tangled.

More particularly, the invention contemplates the construction of an article as mentioned which is characterized by a base, a plurality of vertical posts, and a rod for receiving a spool of thread pivotally mounted on each post, except one end post, and adapted to be pivoted from a vertical position to a horizontal position. In the vertical position a spool of thread may be easily engaged on each rod. In the horizontal position it is proposed that these rods have their free ends rested upon the vertical posts for supporting them in a way to prevent the spools of thread from accidentally coming off.

It is also contemplated to provide a locking mechanism for locking the rods in their horizontal positions.

Still further the invention proposes the provision of a cutter or cutters for the thread mounted on the base by which the thread may be cut when desired.

For further comprehension of this invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a thread holding and cutting device constructed in accordance with this invention.

Fig. 2 is a fragmentary front elevational view of Fig. 1.

Fig. 3 is a plan view of Fig. 2.

Fig. 4 is an elevational view looking in the direction of the line 4—4 of Fig. 2, with certain parts broken away to disclose interior parts.

Fig. 5 is a perspective view of the rods for receiving a spool of thread.

Fig. 6 is an enlarged perspective view of one of the cutters used in the device.

Fig. 7 is a perspective view of a modified cutter for the device.

Fig. 8 is an elevational view of a modified cutter for the device.

2

Fig. 9 is a front elevational view of a thread holding and cutting device constructed in accordance with another form of this invention.

Fig. 10 is a plan view of Fig. 9.

Fig. 11 is a fragmentary enlarged vertical sectional view taken on the line 11—11 of Fig. 10.

Fig. 12 is a horizontal sectional view taken on the line 12—12 of Fig. 11.

Fig. 13 is a vertical sectional view similar to Fig. 11 but illustrated with the parts in a different position.

In the form of the invention illustrated in Figs. 1—5 inclusive, the thread holding and cutting device, in accordance with this invention, includes a base 15 of metal, wood, composition or similar materials. A plurality of vertical posts 16 are mounted in a straight line on the base 15. A rod 17 for receiving a spool of thread 18, is mounted on each of the posts 16, except the post at the extreme left. Each rod 17 is pivotally mounted on the top of the post 16 by a pintle 19. Each rod 17 is of tubular or solid form. At one end it is cut out to have a pair of ears 20. Each post 16 is cut out at the top to have a vertically projecting lug 21. The pintle 19 passes through the lug 21 and the ears 20 and thus pivotally supports the rod.

Each rod 17 is directed towards the left, and has its left end cut out to present a pair of downwardly extending prongs 22. These prongs are adapted to snap over the right hand ends of the adjacent rods 17, except the rod 17 which is at the extreme left. This latter rod is adapted to snap over the top end of the post 16 at the left.

A thread cutter 23 for each spool 18 is mounted on the base 15 to the front of the spool. Each thread cutter 23 comprises a member having a central portion adapted to be attached to the base 15 and a pair of end hooks 24 having sharpened edges beneath which the thread may be engaged and cut.

The operation of the thread holding and cutting device is as follows:

Any one of the rods 17 may be pivoted upwards, as for example, schematically indicated by the dash lines in Figs. 1 and 2. The spool 18 may be slipped off and a new spool applied on the rod. When the rods 17 are in their horizontal positions the threads from the spools may be conveniently drawn off. Each thread may be cut by slipping it beneath the cutting edges of the cutter 23.

In Fig. 7 a modified form of cutter 23' which comprises a blade having a sharp top edge 24', is shown. This blade 23' also has an opening 25 for a fastening element. When this blade is

mounted on a base it is necessary that the base be formed with a slot into which the bottom portion of the cutter 23' be engaged. Then the fastening element may be engaged through the base and into the opening 25 to hold the cutter in position.

In Fig. 8 another cutter 23'' has been illustrated which is of triangular shape and has a V-shaped top cutting edge 24''. Thus cutter 23'' has an opening 25 by which it may be mounted on a base.

The thread holding and cutting device, in accordance with the invention illustrated in Figs. 9 to 13 includes a base 30 of metal, wood, composition or Bakelite, or similar materials. A plurality of vertical posts 31 are mounted in a straight line on the base 30. A rod 32 for receiving a spool of thread, schematically indicated by numeral 33, is pivotally mounted on the top of each post 31, except one end post 31'. Each rod 32 is adapted to be pivoted from a vertical position in which it may be conveniently receive the spool of thread, to a horizontal position in which it supports the spool of thread so that the thread may be drawn off as needed. Means is provided for locking the rods 32 in their horizontal positions.

The locking means mentioned in the latter portion of the previous paragraph functions in a certain way which is characterized by each of the rods 32 sliding into and out of locking positions, as desired. More specifically, each rod 32 is formed with a bayonet slot 34 in the sides thereof, which is engaged by a pintle rod 35 for supporting the rod 32 to pivot and slide. Each bayonet slot 34 has a circular end 34a which when engaged about the pintle rod 35 permits the rod 32 to pivot. Each bayonet slot 34 also has a reduced end 34b which when engaged about the pintle rod 35 locks the rod 32 in a horizontal position. Each pintle rod 35 is mounted across the bifurcated upper end 36 of each post 31. One end of each rod 32 is slightly flattened and the adjacent end of the adjacent rod 32 is slightly enlarged to fit in and about the fingers of the bifurcated end 36, see Fig. 12. A spring 37 is disposed within each rod 32 and is connected between the rod 35 and a pin 38 stationarily mounted across the rod 32. These springs 37 resiliently urge the rods 32 forwards into positions in which the large ends 34a of the bayonet slots 34 encircle the rods 35.

A bracket 39 is mounted upon the vertical post 31' and supports a latching cam 40. This latching cam 40 is turnably mounted on the bracket 39. It is provided with a handle 41 by which it may be conveniently turned. The latching cam 40 is substantially of oval shape. At the ends of its major axis it is provided with niches 42 adapted to engage against and hold the free end of the adjacent rod 32 in a rearward position. The top of the post 31' forms a support for the free end of the adjacent rod 32. The top of the central two posts 31 have rearward projecting side lug portions 43 which form supports for the free ends of the other rods 32. The free ends of these latter rods 32 are provided with small pins 44 which normally engage into apertures 45 formed in an adjacent one of the rods 32.

The operation of the device may be understood from the following:

With the parts as illustrated in Fig. 9 the cam 40 is holding the adjacent rod 32 in a rearward position and this rod 32 is indirectly holding the other rods 32 in rearward positions because of the engagement of the pins 44 in the openings 45. 75

In this condition of the device all of the rods 32 are latched in their horizontal positions because the small ends 34b of the bayonet slots are engaging square pintle rods 35.

5 If it is desired to remove one of the spools 33 it is necessary that the latching cam 40 be turned through 90°. It may be turned by turning the handle 41. This frees the rods 32 and the springs 37 will immediately urge them forwards so that 10 the large ends 34a of the bayonet slots 34 now encircle the rods 35. Any one of the rods 32 may now be pivoted, upwards to vertical position, as for example illustrated in Fig. 13. A spool of thread may be removed or engaged thereon, as desired. The rods 32 may be relocked in their horizontal positions by re-engaging the pins 44 with the openings 45 and re-engaging the large cam 40 with the front end of the adjacent rod 32, as illustrated in Fig. 9.

A thread cutter 48 is mounted upon the base 30. This thread cutter is formed with an upwardly directed end 49 having a downwardly directed knife portion 50, and a downwardly directed end 51 having a knife portion. Thread from any 25 one of the spools may be cut by engaging it against one or the other of the knife portions of the cutter 48.

It is to be understood that the device may be enclosed in a cabinet of any desired shape and 30 material.

While I have illustrated and described the preferred embodiments of my invention, it is to be understood that I do not limit myself to the precise constructions herein disclosed and the 35 right is reserved to all changes and modifications coming within the scope of the invention as defined in the appended claims.

Having thus described my invention, what I 40 claim as new, and desire to secure by United States Letters Patent is:

1. A thread holding device, comprising a base, a plurality of vertical posts mounted in a straight line on said base, a rod pivotally mounted on all except the end one of said posts and adapted to receive a spool of thread, and one end of each rod extending laterally and resting upon an adjacent end of an adjacent rod except the rod adjacent the post without a rod which extends laterally and rests upon the top of the post without the rod, the large ends 34a of the bayonet slots 34 encircling the rods 35.

2. A thread holding device, comprising a base, a plurality of vertical posts mounted in a straight line on said base, a rod pivotally mounted on all except the end one of said posts and adapted to receive a spool of thread, and an end of each rod extending laterally and resting upon an adjacent end of an adjacent rod except the rod adjacent the post without a rod which extends laterally and rests upon the top of the post without the rod, each rod and its post being pivotally connected together with a pintle.

3. A thread holding device, comprising a base, a plurality of vertical posts mounted in a straight line on said base, a rod pivotally mounted on all except the end one of said posts and adapted to receive a spool of thread, and one end of each rod extending laterally and resting upon an adjacent end of an adjacent rod except the rod adjacent the post without a rod which extends laterally and rests upon the top of the post without the rod, each rod and its post being pivotally connected together with a pintle, each rod being formed with a pair of ears through which the pintle passes.

70 4. A thread holding device, comprising a base,

a plurality of vertical posts mounted in a straight line on said base, a rod pivotally mounted on all except the end one of said posts and adapted to receive a spool of thread, and one end of each rod extending laterally and resting upon an adjacent end of an adjacent rod except the rod adjacent the post without a rod which extends laterally and rests upon the top of the post without the rod, the front end of each rod being formed with a pair of downwardly engaging prongs adapted to engage over the adjacent end of an adjacent rod or post in the case of the last rod.

5. A thread holding device, comprising a base, a plurality of vertical posts mounted in a straight line on said base, a rod for receiving a spool of thread and pivotally and very slightly slidably mounted on the top of each post except one end post and adapted to be pivoted from a vertical position to horizontal position supported on said post, means for urging said rods when in their horizontal positions into positions remote from said end post, and means for preventing said rods from pivoting while in said last mentioned positions.

6. A thread holding device comprising a base, a plurality of vertical posts mounted in a straight line on said base, a rod for receiving a spool of thread and pivotally and very slightly slidably mounted on the top of each post except one end post and adapted to be pivoted from a vertical position to horizontal position supported on said post, means for urging said rods when in their horizontal positions into positions remote from said end post, and means for preventing said rods from pivoting while in said last mentioned positions, said means for urging said rods as mentioned above comprising a cam for urging the

endmost rod, and means for connecting all the rods together when in a horizontal position causing them all to be similarly urged when said endmost rod is so urged.

7. A thread holding device comprising a base, a plurality of vertical posts mounted in a straight line on said base, a rod for receiving a spool of thread and pivotally and very slightly slidably mounted on the top of each post except one end post and adapted to be pivoted from a vertical position to horizontal position supported on said post, means for urging said rods when in their horizontal positions into positions remote from said end post, and means for preventing said rods from pivoting while in said last mentioned positions, said means for holding said rods in the remote positions mentioned above comprising a bracket mounted on one of the rods and a latch cam mounted on said bracket engageable with one of the rods to hold it as required.
- 10 8. A thread holding device comprising a base, a plurality of vertical posts mounted in a straight line on said base, a rod for receiving a spool of thread and pivotally and very slightly slidably mounted on the top of each post except one end post and adapted to be pivoted from a vertical position to horizontal position supported on said post, means for urging said rods when in their horizontal positions into positions remote from said end post, and means for preventing said rods from pivoting while in said last mentioned positions, comprising bayonet slots coaxial with the pivoting points of the rods and having enlarged ends engaging the pintles of the pivots which permits pivoting and having reduced ends engaging noncircular portions of the pivots to lock the rods when urged by said means.
